United States Patent Office

Des. 189,466
Patented Dec. 20, 1960

189,466

BOAT

Ben Whitehouse, Jr., 4759 Evans St., Fort Worth, Tex.

Filed Dec. 4, 1957, Ser. No. 48,770

Term of patent 3½ years

(Cl. D71—1)

Fig. 1

Fig. 2

Fig. 4

The side of the boat opposite that shown in Figures 1 and 2 is the same in appearance as the side shown.

I claim:

The ornamental design for a boat, substantially as shown and described.
